GUNNAR G. A. LINDHOLM, OF ANSONIA, CONNECTICUT.

STEAM-ENGINE.

997,627.

Specification of Letters Patent. Patented July 11, 1911.

Application filed February 28, 1911. Serial No. 611,474.

To all whom it may concern:

Be it known that I, GUNNAR G. A. LINDHOLM, a citizen of the United States, residing at Ansonia, county of New Haven, State 5 of Connecticut, have invented an Improvement in Steam-Engines, of which the following is a specification.

This invention relates to steam engines and has for its primary object to provide a 10 novel construction and arrangement of valves and ports that will simplify and improve the working of the engine and will greatly reduce the cost of construction.

With these and other objects in view I 15 have devised the novel engine which I will now describe, referring to the accompanying drawing forming a part of this specification and using reference characters to indicate the several parts.

20 Figure 1 is a longitudinal section of my novel engine complete; and Fig. 2 is a section on the line 2—2 in Fig. 1, looking in the direction of the arrows.

The present invention is especially adapt- 25 ed for two cylinder engines and I have illus- trated it as applied to that type of engine, although the principle is equally applicable to one cylinder or three cylinder engines.

10 and 11 denote the cylinders, 12 and 13 30 the pistons, 14 and 15 the piston rods, 16 the valve chamber and 17 and 18 the valves which reciprocate in the valve chamber and are carried by a valve rod 19 which is pro- vided with a longitudinal exhaust passage

35 20 and with openings 21 and 22 leading into the exhaust passage. Steam is admitted to the valve chamber through a port 29 at its mid length. I preferably form cylinder 10 and the valve chamber in one casting and

40 cylinder 11 in a separate casting which is rigidly secured to the valve chamber as by pairs of corresponding hubs 23 and 24. The wall between cylinder 10 and the valve chamber is provided with ports 25 and 26,

45 and the opposite wall of the valve chamber, hubs 23 and 24 and the contiguous wall of cylinder 11 are provided with ports 27 and 28, port 27 extending from the top of cyl- 50 inder 11 downward through the wall of said cylinder and through hubs 24 and commu-

nicating with the valve chamber below steam port 29, and port 28 extending from the bottom of cylinder 11 and upward through the wall of said cylinder and 55 through hubs 23 and communicating with the valve chamber above steam port 29. In

other words, these ports extend past each other and communicate with the valve chamber on the side of the steam port opposite from their starting point. This arrangement of the ports of one cylinder causes the pistons to move in opposite directions. The heads of cylinders 10 and 11 and of the valve chamber are preferably separate castings, although the head of cylinder 60 10 and of the valve chamber may be made in one casting if preferred.

The operation will be readily understood from the drawing. As shown in the drawing, piston 12 is moving upward and pis- 70 ton 13 is moving downward. Steam is entering cylinder 10 from the valve chamber through port 25 and is exhausting from before piston 12 through port 26 and opening 21 and exhaust passage 20 in the valve 75 rod and steam is entering cylinder 11 from the valve chamber through port 27 and is exhausting from before piston 13 through port 28 and opening 21 and the exhaust 80 passage in the valve rod. As soon as the pistons have reached the extreme of their forward movement, the valve rod and valves will move upward from the position shown so that the valves instead of being below the corresponding ports, as shown in the 85 drawing, will be above them. Steam will now enter cylinder 10 from the valve chamber through port 26 and will exhaust from before piston 12 through port 25 and open- 90 ing 22 and the exhaust passage in the valve 95 rod, and steam will enter cylinder 11 from the valve chamber through hubs 23 and port 28 and will exhaust from before piston 13, through port 27 and hubs 24 and open- 100 ing 22 and the exhaust passage in the valve rod. When the pistons reach the extreme of their forward movement the valve rod and valve will move downward from the position just described to the position shown in the drawing and the taking and exhaust- 105 ing of steam will be again reversed and will be as first described, these operations being continuously repeated while the engine is in use.

Having thus described my invention I 105 claim:

1. An engine comprising a cylinder pro- 110 vided with ports communicating with op- posite ends thereof, said ports having their outer ends in spaced relation, a piston in said cylinder, a valve chamber in communica- tion with said ports and provided with a

- central inlet port, a hollow piston rod slide-
able through said chamber and provided
with ports adapted to be alternately placed
in communication with said cylinder to re-
ceive the exhaust therefrom, a valve car-
ried by said rod and arranged in spaced
relation intermediate of the piston ports for
controlling the exhaust from the cylinder
ports.
- 5 10 2. An engine comprising a pair of cylin-
ders, pistons therein, one of said cylinders
being provided with upper and lower ports,
a valve chamber interposed between said cyl-
inders and provided with an admission port,
15 the other cylinder having one port that
places its upper portion in communication

with the lower portion of said chamber
and another port that places its base in
communication with the upper portion of
said chamber, a hollow rod provided with 20
upper and lower ports for receiving the ex-
haust from said cylinder ports, and valves
carried by said piston rod and arranged in
spaced relation to control the exhaust from
said cylinders.

25

In testimony whereof I affix my signature
in presence of two witnesses.

GUNNAR G. A. LINDHOLM.
